YARN CARRIER STOP DEVICE FOR
STRAIGHT KNITTING MACHINES

Emil Richter, Spring Crest Courts, Pa., assignor,
by mesne assignments, to Textile Machine
Works, Wyomissing, Pa., a corporation of Penn-
sylvania

Application March 6, 1934, Serial No. 714,235

1 Claim. (Cl. 66—129)

My invention relates to straight knitting machines, and particularly to yarn carrier stop means for limiting or arresting the movement of the reciprocative carrier rods, or equivalent elements, in such machines.

In the production of certain fabrics, especially full fashioned stockings, it has been found desirable or necessary to modify or vary the throw of selected yarn carrier rods as ordinarily established by the usual yarn carrier stop mechanism of the knitting machine, i. e., so that the throw of one or more of the yarn carrier rods is greater or less than that ordinarily established by the usual carrier stops employed.

For example, and by way of illustration only, it is customary to protect the heel and toe portions of a stocking against the extra wear ordinarily occurring at these places, by adding to these portions one or more reinforcing or plating yarns interknit with the main body yarn, such result being obtained, after knitting the leg portion of the stocking blank to the place where the reinforcement begins, by placing in operation additional yarn carrier rods for laying the extra or reinforcing yarns. Heretofore, these rods have had the throw thereof determined by the usual end and intermediate stops of the machine, and since the respective end stops of each group at the ends of the machine move only in unison, the limit of travel of the reinforcing carrier rods at the selvedge edges of the blank has coincided with that of the main body yarn carrier, thus causing the reinforced areas to extend to and be included in, the selvedge edges.

When the opposite selvedge edges of the stocking blank are looped or stitched together, there ordinarily results a seam of considerable bulk which is uncomfortable to the wearer and unsightly in appearance. These disadvantages may be obviated by the use of the present invention, since when a reinforcing yarn or yarns have been laid by the plating carriers to a point short, by a certain distance, from each selvedge edge of the blank, as by the width of two or three wales, the plating carrier rods may be arrested at this point by the stop devices disclosed herein, the movement of the through or main yarn carrier rod continuing to the selvedge edge; this operation resulting in the production of a selvedge edge or margin of reduced thickness, relative to the reinforced areas of the fabric, from which a seam of the desired characteristics may be formed. By permitting the main yarn carrier only to continue to the selvedge edges, the latter will be free from reinforcement; by causing one of the plating car-

riers at each side of the blank to also continue to the selvedge edges, the same may be reinforced, but to a degree less than that of the adjoining areas in which additional reinforcing yarns are employed.

Since in the usual practices of knitting, the machines, as heretofore constructed, have not to my knowledge been adapted to effect the foregoing operation in a satisfactory, rapid or effective manner, it is an object of the invention to overcome the disadvantages of lack of these features, and to provide an auxiliary carrier stop device for modifying or supplementing the action of the usual carrier stops, which device is simple and durable in construction, economical to manufacture and effective in its operation.

Another object of the invention is to provide an auxiliary stop device adapted to installation on machines of standard construction, and to existing installations, with a minimum of labor, expense and structural alteration.

Another object of the invention is to provide a stop device for modifying the action of the usual stop members, which device shall be in the nature of a readily-available and operable auxiliary attachment or appertenance, for quick and convenient manipulation incident to the knitting operations; as distinguished from calibrating or set adjustment devices, such as screws and lock nuts, or the like.

Another object of the invention is to provide a device in which certain parts may be readily interchanged and renewed, either to compensate for wear or to vary the throw of the carrier rods in accordance with different requirements.

Another object of the invention is to provide a knitting machine attachment that shall be positive and accurate in operation, and permit adjustments of fine degree.

A further object is to provide in combination with the end stops of a straight knitting machine, an auxiliary stop device which can quickly and easily be thrown into and out of operation, thereby to change at will the throw of the yarn carrier rod controlled by the end stop.

With these and other objects in view, which will become apparent from the following detailed description of the illustrative embodiments of the invention shown in the accompanying drawing, my invention resides in the novel elements of construction, devices and combination of parts in cooperative relationship, as hereinafter more particularly pointed out in the claims.

In the drawing:

and having distance breaks, of the carrier rods, stops and associated parts of one section, of a full-fashioned knitting machine, to which one embodiment of my invention has been applied;

5 Fig. 2 is a view, in front elevation and enlarged to substantially actual scale, of a portion of the device, as viewed at the left-hand side of Fig. 1, with parts thereof omitted, and other parts added, which are not shown in Fig. 1;

10 Fig. 3 is a view taken substantially along the line 3—3 of Fig. 2;

Fig. 4 is a view, corresponding to a portion of Fig. 2, but on a larger scale and having portions broken away and other parts in section, of a modified form of the invention;

15 Fig. 5 is a view of the structure of Fig. 4, taken at right angles thereto;

Fig. 6 is a view, similar to Figs. 2 and 5, of a further modified form of the invention;

20 Fig. 7 is a view of a portion of the structure of Fig. 6, taken substantially along the line 7—7 thereof;

Fig. 8 is a plan view of the toe section of a stocking, fabricated by a machine embodying the 25 invention; and

Fig. 9 is a view representing a magnification of areas E of Fig. 8, and indicating the detail loop structure thereof.

In the drawing, only those parts of a full-fashioned knitting machine necessary to a complete understanding of the invention are therein shown, the various other parts, and the operation thereof being well known in the art, and shown and described in detail in the "Reading" Full Fashioned Knitting Machine Catalogue, copyright 35 1929, published by the Textile Machine Works, Reading, Pennsylvania.

The auxiliary stop devices of the invention may be employed either with the carrier rod end stops 40 or the intermediate stops of a straight or full-fashioned knitting machine to vary, for any purpose, at the selvedge edges, or intermediate the selvedge edges, of a fabric, the throw of a selected yarn carrier or carriers as ordinarily established 45 by the end and intermediate stops. The end stops, at each end of the machine, are moved in unison, no individual or relative adjustment being provided, except that of initial installation or calibration, which may also require occasional 50 change by reason of damage or wear. According to the illustrative embodiment of the invention, the auxiliary stop elements are provided for selective cooperation with the usual end stops whereby to reduce the throw of the associated 55 carrier rods, without affecting the throw of the other rods as determined by the end stops associated with such other rods; these auxiliary elements being in the form of gauge plates or strips for insertion between the rods and the 60 ordinary stops, or they may be in the form of eccentric cams for moving the ordinary stops, or of any equivalent form, either on the stationary or movable parts, as will be more apparent from the following description and the accompanying 65 drawing.

Referring to Figs. 1, 2, and 3, carrier rods 10, each of which carries thread carriers 11 for cooperation with the usual needles 8 and sinkers and dividers 9 in the various knitting sections, one 70 of which sections is indicated at the lower portion of Fig. 2, are longitudinally reciprocably mounted between sets of end stops 12. Pivot pins 14, on which the stops 12 are mounted, are secured, as by brackets 15, to nuts 16 on a usual feed screw 75 or carrier rod spindle 17. A screw 18, in the lower

portion of each stop 12, is locked in position by a nut 19, and has a head 20 for arresting the movement of the cooperating carrier rod 10. Calibrating adjustments, to originally set the throw of the rods 10 and to compensate for wear, are 5 effected by manipulation of the screws 18 and the nuts 19.

As so far described, the structure of Figs. 1, 2, and 3 is usual, the stops 12 being individually pivoted on the pins 14 for selectively throwing the 10 heads 20 about these pivots into, and out of, the operative position shown, by manipulation of handles 22. The screw 17 remains stationary except when the stocking blank is to be narrowed, at which time rotation of the screw moves the 15 stops inwardly in unison to a new position to thus reduce the throw of the rods 10.

In accordance with a preferred form of the invention, as indicated in Figs. 1, 2, and 3, an auxiliary stop, for each of any desired or required 20 number of the main stops 12, may comprise a lever 23 having a bifurcated end 23a embracing the handle 22 and pivotally secured thereto, as by a pin 24. A groove or channel 23b, in the face of the lever 23 next to the carrier rod 10, 25 receives a gauge plate or strip 25, the thickness of which is determined by the number of wales by which it is desired to reduce the ply of a selvedge edge of a stocking, as will further appear. The plate 25 is preferably secured to the lever 23, 30 as by a screw and lock-washer device 26; all of the parts being accurately machined for precision fit, and related to prevent subsequently working loose, as in the feature whereby the strip 25 is disposed in the recess of the lever 23 and accurately held at its edges, in addition to the holding effect of the screw 26, and in the feature wherein the arms of the bifurcated end of the lever 23 operate in broad-area engagement with, and over, cooperating areas on the sides of the handle 22. 35

As indicated on one of the handles 22, at each end of the rods 10, and in full lines in Fig. 2, the lever 23 is in position to hold the strip 25 between the carrier rod 10 and the corresponding head 20, thus reducing the throw of the rod to 40 less than the ordinary by a distance equal to the thickness of the gauge strip 25. The thickness of this strip may be such as to provide a selvedge edge of reduced thickness of any desired number of wales and be one of a set of interchangeable strips for changing this number; the strip of Figs. 1, 2, and 3 being of a thickness to provide a selvedge edge of reduced thickness of two wales. 45

As shown in Fig. 8, the instep section of a stocking has a single-thread web area A, a reinforced area B of double-thread thickness, and a further reinforced area C of triple-thread thickness, on the latter of which, as shown to magnified scale in Fig. 9, is provided a reinforced selvedge edge D of reduced thickness relative to the 50 adjacent three-thread reinforced toe portion, the construction being readily producible with the device of the present invention. In this case, the edge D is preferably stepped down, by one thread, to be of two-thread thickness, although it 55 may be stepped down to a single-thread thickness, and be of any desired number of wales and thread relative to the area C, the width of the edge in number of wales being determined by the particular strip 25 selected.

In Figs. 4 and 5, the screw 18b has a constricted portion 28 surrounded by a ferrule 29 and holding a headed screw 30, between which and the inner end of the ferrule, a helical spring 32 surrounds the constricted screw portion to bias 75

the ferrule inwardly along the screws, or to the left as viewed in Fig. 4. A flange 33 and a screw-threaded portion 33a outwardly thereof on the ferrule, provide seats for a wear or gauge head 34. 5 A gauge plate or strip 25b, including a lower end portion 36 of inverted substantially U-shape having beveled lower edges, an upper end handle or grip 37, and a vertical straight-sided central slot 39, is vertically slidably fitted against the stop 12b, as by a screw 40 on which is mounted 10 a member 42 constituting a rectangular guide for the strip in the slot 39.

To operate this device, it is merely necessary to move the strip 25b from its frictionally held, 15 or otherwise secured, upper position to a lower position, during which the head 34 is moved to the right, as viewed in Fig. 4, against the action of the spring 32, and held by the spring against the strip.

20 In Figs. 6 and 7, the parts adjacent to the carrier rod are constructed as in an ordinary stop, and the adjustment of the invention obtained by mounting the stop 12c, as a unit, upon an eccentric cam portion 44 of the pivot pin or shaft 14c, 25 about which the stop may be pivoted, in its ordinary stop function, and by which it may be moved from left to right, as viewed in Fig. 6, by turning a knurled handle extension 45. A radial pin 46 has snug frictional-sliding fit in a radial aperture in the bracket 15c for similar fit in a radial hole or holes 47 in the shaft 14c.

By radially moving the pin 46 clear of the pin 14c, the handle 45 may be manipulated to turn the shaft to any desired position, and the pin 46 returned to again lock the shaft; this operation adjusting the stop 12c and the head 20 to vary the throw of the carrier rod, as in the devices above set forth.

Of course, the improvements specifically shown 40 and described, by which I obtain the above results, can be changed and modified in various ways without departing from the scope of the invention herein disclosed and hereinafter claimed. Further, it is to be understood that the

means specified in the claim for stopping a selected carrier rod an incremental distance ahead of a cooperating carrier rod, includes any element or combination of elements which acting together or singly, causes a selected carrier rod to stop 5 ahead of a cooperating carrier rod moving in unison therewith, whereby the end of a selected carrier rod is spaced an incremental distance from the end of a cooperating rod when both rods have completed their effective strokes in one direction. That is to say, the above-mentioned means defines any means for stopping a selected carrier rod longitudinally ahead of a cooperating carrier rod by an increment of distance.

I claim:

In a straight knitting machine having a plurality of yarn carrier rods, the combination of a movable head having a stop member thereon for each of said rods, each of said stop members provided with an abutment member adjustable 20 with respect thereto and each stop member mounted to be moved selectively into and out of the path of a yarn carrier rod and having a handle portion projecting above the abutment surface of said abutment member, and a lever forked 25 at one end and having its forked end portion pivoted to the handle portion of one of said stop members on opposite sides of said handle portion and having an extension plate of reduced thickness fixed to its other end, said lever arranged 30 to be thrown so said extension plate will hang down in contact with the abutment surface of the abutment member of the stop member to which the lever is attached to vary the throw of the yarn carrier rod with which the stop member coacts by a uniform amount irrespective of the position of the abutment surface of the abutment member relative to such stop member and said lever and stop member arranged so that 35 the lever may be thrown back and will lie above the stop member to hold the lever in inoperative position by gravity.

EMIL RICHTER.
